UNITED STATES PATENT OFFICE.

EMANUEL DRESNER, OF CHICAGO, ILLINOIS.

FASTENER.

Application filed April 2, 1925. Serial No. 20,143.

My invention relates to luggage and more specifically to an improved lock for holding in closed position the parts of a piece of luggage built to be opened up for access to the interior. It is particularly useful in connection with Gladstone bags, on account of the structural weakness of the double hinge, and the resultant necessity for supporting both frames when the bag is carried.

10 Among the objects and advantages of the invention may be enumerated:

First, to provide a fastener for luggage frames forming a strong positive tension connection for holding the frames together 15 at the point of engaging.

Second, to use nearly all of the structure of the old type of fastener in so doing.

Third, to retain the operation of the fastener formerly employed, with which users 20 are already familiar, and to perform the additional fastening operation in such a way as to minimize the manual effort and thought required of the user.

Further objects and advantages of the 25 invention will become apparent as the description proceeds.

In the accompanying drawings:

Figure 1 is a side elevation of the complete assembly of the external portion of a 30 fastener according to the invention;

Figure 2 is a central transverse section with the lock in locked position;

Figure 3 is a section on line 3-3 of Figure 2;

35 Figure 4 is a section on line 4-4 of Figure 1;

Figure 5 is a section on line 5-5 of Figure 3; and

40 Figure 6 is a side elevational diagram of a complete bag indicating the location of the various fasteners.

In the embodiment of the invention selected for illustration, the dished housing 10 is provided with attaching lugs 12 adapted 45 to pass through openings 14 in the frame 16, hereinafter referred to as the bag or handle frame, and to be clinched over to hold the housing in place. An upper pivoted arm plate 18 is mounted on a transverse pintle 20 in the housing 10, and may move 50 from the position shown in Figure 1 down to that shown in Figure 2 with its depending side flanges 22 abutting the housing 10. A leaf spring 24 bears against suitably dis-

posed flats or projections 26 to bias the arm 55 toward either extreme position.

In the devices of the prior art this arm carried an arcuate tang adapted to slide through a registering aperture in the front frame 28. While this was adequate to protect against horizontal separation of the frames from the position shown in Figure 5, the inclined edge of the tang where it passed through frame 28 allowed the dead weight carried by frame 28 and pulling down on the same to separate the frames vertically, pulling sideways and warping all the parts. This tendency was particularly bad in Gladstone bags because the double hinge at the bottom of the bag will not 70 support frame 28 at all.

In place of such a tang, I employ a bolt element 30 pivotally mounted in arm 18 about its own axis, which is perpendicular to the plane of the arm. Frame 28 has its upper leg cut away at 32 where the loop 34 is suitably attached as by rivets 36 fastening the loop to the vertical leg. The slot 38 receives bolt 30, which, at least where it passes through said slot, is flattened and provided with side notches 40 positioned to register with slot 38 and permit rotation of the bolt to the position shown in Figure 2, in which position any force tending to separate frame 28 vertically from frame 16 85 is carried by direct tension in the bolt. Beyond slots 40 I continue the bolt to form a head 42 having V-shaped notches 44. To prevent rotation of arm 18 beyond the position in Figure 1, the parts are so proportioned that the remote shoulders of notches 44 will underlie housing 10 at the end of the slot 46. Notches 44 are provided on both sides so that the bolt can be turned completely around without interfering with the 95 operation.

I have provided suitable means for pivotally supporting bolt 30 on arm 18 and for biasing it toward either the fastened or the unfastened position. In the present instance this means comprises a flange 48 abutting the upper surface of arm 18, a transverse pin 50 below the arm, and a resilient plate 52 stamped out of light sheet metal, having grooves 54 adapted to receive pin 50 100 and elevated areas 56 adapted to press against the pin and bias it toward the grooves. The plate is made square and of

suitable dimensions to abut flanges 22, thereby holding itself against rotation, and the insertion of pin 50 completes the assembly without the necessity of any other fastening 5 means.

Figure 6 illustrates a complete bag having a handle 58, a key lock 60 and two fasteners 62 according to Figure 1. The key lock also provides a tension connection so 10 that frames 16 and 28 are closely bolted together at three different points. The upward force exerted on handle 58 is communicated in the first instance to frame 16 only, at two spaced points. Each point is located 15 intermediate the key lock 60 and one of the end fasteners 62; end fasteners 62 being preferably positioned a little farther from the ends of the handle than the key lock 60, to get them a little nearer the ends of the bag 20 as a whole, and more efficiently transmit the force to the bottom hinges located at 64.

Without further elaboration, the foregoing will so fully explain the gist of my invention, that others may, by applying current knowledge, readily adapt the same for 25 use under various conditions of service, without eliminating certain features which may properly be said to constitute the essential items of novelty involved, which items are 30 intended to be defined and secured to me by the following claims.

I claim:

- 35 1. A lock for luggage comprising a housing, an arm pivoted on said housing to lie flat on top of the same or swing up at an angle thereto, and a bolt pivoted about its own axis normal to said arm to project through said housing and fasten an element below the same.
- 40 2. A lock for luggage comprising a housing, an arm pivoted on said housing to lie flat on top of the same or swing up at an angle thereto, and a bolt pivoted about its own axis normal to said arm to project through said housing and fasten an element below the same, said bolt having a portion positioned to engage said housing and limit outward movement of said arm.

3. A lock for luggage comprising a housing, an arm pivoted on said housing to lie 50 flat on top of the same or swing up at an angle thereto, and a bolt pivoted about its own axis normal to said arm to project through said housing and fasten an element below the same, said bolt having irregularities of contour moved into and out of engagement with said element by rotation of the bolt about its own axis.

4. A lock for luggage comprising a housing, an arm pivoted on said housing to lie 60 flat on top of the same or swing up at an angle thereto, a bolt pivoted about its own axis normal to said arm to project through said housing and fasten an element below the same, and resilient means biasing said bolt 65 toward locked or unlocked position.

5. A lock for luggage comprising a support, a bolt passing through said support and movable by rotation about its own axis, said bolt having a shoulder on one side of 70 said support, a transverse pin in said bolt out the other side of said support, and a leaf spring held between said pin and support to bias the bolt to fastened or unfastened position, said leaf spring and support having 75 registering irregularities of contour to hold said spring against rotation about the axis of the bolt.

6. A fastener comprising a body, an arm pivoted on said body to move toward and 80 away from the same, and a bolt pivoted on said arm for rotation about an axis at an angle to said arm, said bolt having irregularities in contour operative when said arm is moved toward said body to fasten an element 85 moved into alignment with the bolt axis.

7. A fastener comprising a body, an arm pivoted on said body, and a bolt pivoted on 90 said arm for rotation about an axis at an angle to said arm, said bolt having irregularities in contour to fasten an element moved into engagement therewith.

In witness whereof, I hereunto subscribe my name this 25th day of March, 1925.

EMANUEL DRESNER.
